UNITED STATES PATENT OFFICE.

JOHN GABEL, OF CHICAGO, ILLINOIS.

DESIGN FOR A MERCHANTISE-CABINET.

SPECIFICATION forming part of Design No. 35,048, dated September 3, 1901.

Application filed August 9, 1901. Serial No. 71,428. Term of patent 7 years.

To all whom it may concern:

Be it known that I, JOHN GABEL, a resident of Chicago, in the county of Cook and State of Illinois, have invented a certain new and original Design for a Merchandise-Cabinet, of which the following is a specification, reference being had to the accompanying drawing, forming a part thereof.

The drawing is a perspective view of the cabinet embodying my design.

As shown in the drawing, the leading or most characteristic feature of my design comprises a cabinet-body 10, provided with an ornamental front having three sections—a lower rectangular section 11, a narrow rectangular central section 12, and an upper section 13. The lower rectangular section 11 is provided with ornamental columns 14

at its side edges and with a central rectangular ornamental panel 15, having an edge molding 16. The rectangular central section is rearwardly inclined, and its surface is provided with ornamental bosses and edges, as shown in the drawing. The upper section 13 is curvilinear in outline and provided with 25 interlacing scrolls about a central plane surface 17.

Having thus described my invention, what I claim as new, and desire to secure by Letters Patent, is—

The design for a merchandise-cabinet, substantially as herein shown and described.

JOHN GABEL.
